FLASHLIGHT

Otto Deose, Clifton, N. J., assignor to Bright Star
Battery Company, Clifton, N. J., a corporation
of New Jersey

Application December 15, 1945, Serial No. 635,278

1 Claim. (Cl. 200—60)

1

This invention relates to flashlights.

An object of this invention is a flashlight of such construction that it is waterproof.

In a flashlight embodying this invention, gaskets are provided to insure a water-tight seal between the tube and the cap and between the lens ring assembly and the tube. In addition, a fixed and a movable contact are supported in a slot or recess in the tube with a flexible moisture-impervious diaphragm overlying them and hermetically sealing the slot or recess. Exterior of the tube are provided means for flexing the diaphragm to engage the diaphragm with the movable contact and advance it into engagement with the stationary contact. With this arrangement, moisture is effectively excluded from the interior of the flashlight.

Other objects, novel features and advantages of this invention will become apparent from the following specification and accompanying drawings, wherein:

Fig. 1 is an elevation of a flashlight embodying the invention;

Fig. 2 is a section on the line 2—2 of Fig. 1;

Fig. 3 is an enlarged fragmentary view similar to Fig. 2; and

Fig. 4 is a view similar to Fig. 3 of a modification.

The flashlight comprises a tube 10 of molded insulating material such, for example, as cellulose acetate in the form commercially known as Lumarith, said tube having a flaring head 11 at 13. A lens 14 rests on an annular gasket 15 which in turn rests on the flange 16 of a reflector 17. A metal ferrule 18 in the head 11 provides a shoulder on which rests the flange 16. The lens, gasket and reflector are held in assembled relation by pressure applied to the lens 14 by the lens ring 12. A gasket 19 is interposed between the lens ring and head 11.

In the end of the tube 10 opposite the flared head 11 is molded a threaded ferrule 20. A metal sleeve 21 threaded at one end is molded into a hollow base cap 22 of Lumarith with the threaded portion projecting beyond the cap, this threaded portion being screwed into the threaded portion of the ferrule 20. A gasket 23 is interposed between the cap 21 and tube 10.

In the embodiment of Figs. 1 to 3 inclusive, the tube 10 is provided with an aperture 24 approximately midway its ends. A conductive strip 25 is attached to the inner surface of the tube 10 and communicates in a portion extending into the aperture 24 to form a stationary contact 25a. A second conductive strip 26 is fixed to the interior of the tube and extends from the ferrule 18 to the aperture 24 and terminates in a flexible portion also constituting a movable

2

contact 27. The end of the movable contact 27 overlies and is biased away from the stationary contact 25. A flexible diaphragm 28 is hermetically sealed to the outer surface of tube 10 and closes the aperture 26. A contact box 29 fits over the diaphragm 28 and is attached to the tube 10 by any suitable means.

In the contact box 29 is arranged a stationary strip 30 of flexible metal in overlying relation to the diaphragm 28 and having a struck-out portion constituting a tongue 31 adapted for flexion. The free end 31a of the tongue 31 is offset from the strip 30 toward the diaphragm 28 and the tongue is formed with an oblique surface 32 adjacent said offset end. A button 33 exterior of the box 29 has extensions 33a passing through slots in the box to slidably support a metal strip 34 for reciprocation within the box. One end 34a of the strip 34 is offset downwardly in position to engage the oblique portion 32 of the tongue 31.

With the button 33 and member 34 in the position shown in Fig. 3, the end 34a overlies the end 31a of the tongue 31 and movement of the member 34 to the left engages the end 34a with the oblique surface 32 to move the free end 31a of the tongue 31 downwardly, thereby downwardly flexing the diaphragm 28 and moving the contact 27 into engagement with the contact 25, such engagement being maintained as long as the member 34 is maintained in its left-hand position due to the fact that the end 34a of the member 34 has ridden up the full length of the oblique surface 32 into engagement with the flat portion of the member 31 beyond the oblique portion. Upon return of the member 34 to the position shown in Fig. 3, the tongue 31 is released and the contact 27 returned to the position shown in Fig. 3. The member 34 is provided with an extension 35 underlying a push button 36 mounted in the contact box 29. A tongue 37 struck out from the contact box 29 underlies the free end of the extension 35 when the member 34 is in the position shown in Fig. 3, thereby locking the member 34 against flexion. However, upon slight movement of the member 34 to the left from the position shown in Fig. 3, the extension 35 is disengaged from the tongue 37 and the member 34 may be flexed by inward movement of the button 36 to engage the offset end of the member 34 with the free end 31a of the tongue 31 to flex the diaphragm 28 downwardly and engage the movable contact 27 with the stationary contact 25.

In the modification of Fig. 4, a closed bottom recess 40 is formed in the outer surface of the tube 10 with three holes 41 leading through the bottom of the recess into the interior of the tube 10. A strip 42 of Bakelite or other similar material is arranged at the bottom of the recess 40.

and has holes in alignment with the holes 41. A metal rivet 43 passes through one set of holes in the recess bottom and Bakelite strip and holds the conductive strip 24a in place. A strip of resilient metal 44 overlies the Bakelite strip 42 and has holes aligned with the two remaining sets of holes through the strip 42 and the bottom of the recess. Metal rivets 45 extend through the aligned holes into the interior of the tube and hold the conductive strip 26a in place. The metal strip 44 has an offset portion 46 overlying the rivet 43. The strip 44 and the rivet 43 constitute a movable and a fixed contact respectively. A flexible moisture-proof diaphragm 28a overlies the metal strip 44 and rests on a ledge 47 formed in the wall of the recess 40, the diaphragm being hermetically sealed to the ledge.

A contact box 48 overlies the diaphragm and is held in place by screws 49 threaded into eyelets 50 set into the wall of the recess. Within the contact box is a stationary strip of resilient metal 51 having a portion cut-out to form a tongue 52 having a bowed portion 53. The free end 52a of the tongue 52 overlies the diaphragm 28a directly above the offset portion 46 of the metal strip 44. A button 54 exterior of the box 48 has extensions 54a passing through slots in the ports to slidably support a metal strip 55 for reciprocation within the box. The slide 55 has an offset portion 56 which in one position of the slide 55 is adapted to engage the bowed portion 53 of the tongue 52.

With the slide 55 in the position shown in Fig. 4, the offset 56 is out of engagement with the bowed portion 53 and the offset portion 46 of the contact 44 is out of engagement with the contact 43. However, upon movement of the slide 55 to the left, the offset 56 engages the bowed portion 53 to depress the free end 52a of the member 52 against the diaphragm 28a to flex it into engagement with the offset portion 46 of the strip 44 to engage said portion 46 with the rivet 43.

The slide 55 is supported by the button 54 in such manner that its right end is capable of flexion. However, with the slide 55 in the position shown in Fig. 4, the right end of the slide engages a tongue 57 struck out from the contact box 48 and is held against flexion. Slight movement of the slide 55 to the left disengages its right end from the tongue 57 whereupon the slide may be flexed by depression of the button 58 mounted in the contact box, thereby engaging the offset 56 with the end 52a of the tongue 52 to depress it sufficiently to cause engagement of the offset portion 46 of the metal strip 44 with the rivet 43.

In each embodiment, location of the button 33 or 54 in its extreme left position closes the flashlight circuit and maintains it closed, while location of the button in its extreme right-hand position prevents operation of the flashlight by preventing flexion either of the tongue 31 or the member 55. In an intermediate position, the circuit in each embodiment may be closed by depressing either the button 33 or the button 54.

The provision of the hermetically sealed diaphragm 28 or 28a, together with the gaskets 15, 16 and 17 renders the flashlight casing waterproof. The contents of the flashlight, therefore, are protected against deterioration from the effects of moisture.

It is of course understood that various modifications may be made in the flashlight structure herein described, without in any way departing from the spirit of the invention as defined in the appended claim.

I claim:

A flashlight comprising a tube of insulating material having an outwardly facing recess, a pair of conductors in said tube and underlying said recess, said conductors being spaced apart and electrically insulated from each other, a metallic rivet-like member extending through said casing in the recess and being secured to one of said two conductors, said rivet-like member constituting a stationary electrical contact, a metallic leaf spring positioned in said recess, metallic means extending through said casing and securing said leaf spring electrically to the second of said two conductors in said casing, said leaf spring having an offset portion acting as a movable electrical contact overlying the metallic rivet-like member and normally spaced apart therefrom, a flexible moisture proof diaphragm fitted within said recess, said recess having a ledge on which said diaphragm rests and to which said diaphragm is hermetically sealed, a stationary strip of resilient material having an outwardly bowed tongue, one end of said tongue being free, said stationary strip overlying the diaphragm directly above said offset portion of said leaf spring, a contact box overlying said stationary strip, means for securing said contact box and said stationary strip fixedly to said tube and over said recess, a slidably flexible strip within said contact box, said flexible strip having an offset portion, button means externally carried on said contact box for slidably supporting said slidable strip internally of said box with one end of said slidable strip free for flexion, said button means also being operable to slide said slidable strip, locking tongue means on said contact box with which said one end of said slidable strip is engageable in one of its slidable positions to then preclude flexion of said slidable strip, a second button means extending outwardly of said contact box and overlying the offset portion of said slidable strip, said last-named offset portion being engageable with said outwardly bowed tongue of said stationary strip in a second of the slidable positions of said slidable strip to thereby flex said diaphragm and maintain said offset portion of said leaf spring in contact with said metallic rivet-like member, and said offset portion of said slidable strip being engageable with said outwardly bowed tongue of said stationary strip in a position intermediate the said two slidable positions of said slidable strip only upon manual depression of said second-named button means to thereby only then flex said diaphragm and then maintain said offset portion of said leaf spring in contact with said metallic rivet-like member.

OTTO DOOSE.
